CLAIM

The ornamental design for a package of consumable sticks,
as shown and described.

DESCRIPTION

FIG. 1 is a front and top perspective view of a package of consumable sticks, showing the new design.

FIG. 2 is a front elevational view thereof.

FIG. 3 is a rear elevational view thereof.

FIG. 4 is a top plan view thereof.

FIG. 5 is a bottom plan view thereof.

FIG. 6 is a right side elevational view thereof; and,

FIG. 7 is a left side elevational view thereof.

The broken lines, the areas within them, and the unshaded areas bounded by both broken and solid lines depict portions of the package of consumable sticks that form no part of the claimed design.
